Filed July 16, 1970, Ser. No. 24,004

Claims priority, application Italy May 29, 1970

Term of patent 14 years

Int. Cl. D9—01

U.S. Cl. D9—10

FIG. 1 is a top plan view of a combined bottle, wrapping and product identification label showing my new design;

FIG. 2 is an elevational view;

FIG. 3 is an elevational view showing the side opposite that seen in FIG. 2;

FIG. 4 is an elevational view looking from the right of FIG. 2; and

FIG. 5 is a bottom plan view thereof.

I claim:

The ornamental design for a combined bottle, wrapping and product identification label, as shown.
